UNITED STATES PATENT OFFICE.

WILHELM ARNEMANN, OF HAMBURG, GERMANY.

PITCHING-MACHINE.

SPECIFICATION forming part of Letters Patent No. 466,027, dated December 29, 1891.

Application filed October 9, 1891. Serial No. 408,228. (No model.)

To all whom it may concern:

Be it known I, WILHELM ARNEMANN, of the city of Hamburg, in the Empire of Germany, have invented a new and useful Improvement 5 in Pitching-Machines, of which the following is a specification.

The object of this invention is to provide an arrangement which will completely do away with an exhauster for drawing the smoke 10 out of the barrels being pitched, and is an improvement upon the machine shown, described, and claimed in United States Patents Nos. 440,296 and 440,297, granted to me on the 11th day of November 1890.

15 A practical embodiment of my invention is shown in the accompanying drawings, in which—

Figure 1 is a vertical sectional view of a pitching-machine with my improvement embodied therein. Fig. 2 is a top plan view of the same; and Fig. 3 is a side view of the same, partially in section, showing the pipe for conveying the smoke away from the smoke-chamber, leading to an independent 25 furnace, where it may be utilized as fuel.

The furnace employed for furnishing heat to the pitching apparatus consists of a lower compartment A and upper compartment A'. A tube a for conveying fresh air from any 30 suitable blower enters the bottom of the furnace. Tubes a' a' extend from the tube a into the top of the lower compartment A. Tubes B extend from the upper compartment A' in a downward direction for a distance 35 and then turn outwardly and upwardly, and are provided with spraying-nozzles b, which are adapted to enter the barrel to be treated through the bung-hole. A chamber C surrounds the outwardly and upwardly turned 40 portion of each of the tubes B. The said chamber has a turned-up open portion c, upon which the barrel D is adapted to seat and close said opening. Branch pipes c' lead from the chamber C to the main pipe c², and thence to a chimney, furnace, sewer, or other well-known means for utilizing or conveying the smoke away. The products of combustion, in passing from the upper compartment 45 A' through the tubes B into the barrel to be pitched, heat the air in the chamber C, thereby rarefying it and thereby inducing a draft, which will draw the smoke out of the barrel D into the chamber C, and thence through

the pipes c' to the main pipe c², and thence to the chimney or other outlet. I may also 55 provide a small tube E, leading from the upper compartment A' into the main pipe c², through which a portion of the products of combustion is allowed to escape to increase the draft, so as to draw the smoke through 60 the pipes c' with greater rapidity. The bottom of the chamber C is preferably made slanting downwardly and outwardly, and at its lower end is provided with an opening c³, through which any pitch which may escape 65 from the barrel may pass to any suitable receptacle F.

In Fig. 3 I have shown the main pipe c², leading to a furnace, whereby the smoke may be consumed. 70

By the above arrangement of a chamber around a portion of the hot-air tubes B, I am enabled to draw all the smoke and gases out of the barrel and carry them away without the aid of an exhauster, thereby simplifying 75 the machine in a material degree.

What I claim is—

1. In a pitching-machine, the combination, with a furnace, of a hot-air tube leading therefrom and provided with a nozzle, a chamber 80 surrounding a portion of said tube, the said chamber being provided with a suitable outlet-pipe, substantially as set forth.

2. In a pitching-machine, the combination, with the furnace, hot-air tube, and nozzle, of 85 a chamber embracing a portion of the hot-air tube, a branch pipe leading from the chamber, and a main pipe leading to a suitable outlet, said furnace having an opening leading therefrom into the main pipe for accelerating the draft, substantially as set forth. 90

3. In a pitching-machine, the combination, with a furnace, of a hot-air tube leading therefrom and provided with a nozzle for insertion into the vessel to be pitched, a chamber embracing the said tube and provided with an open seat upon which the said vessel is adapted to rest and close said opening, a main pipe leading to a suitable outlet, and a branch pipe connecting said chamber with the main 95 pipe, substantially as set forth. 100

WILHELM ARNEMANN.
